(57) **CLAIM**

The ornamental design for a lid for fresh keeping box, as shown and described.

DESCRIPTION

FIG. 1 is a first perspective view of a lid for fresh keeping box showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the lid for fresh keeping box in which the design is embodied that form no part of the claimed design.
